Inventor
George Whitfield Chance,

UNITED STATES PATENT OFFICE.

GEORGE WHITEFIELD CHANCE, OF SWARTHMORE, PENNSYLVANIA.

BUILDING CONSTRUCTION.

Application filed June 13, 1922. Serial No. 567,925.

My invention relates to improved methods of building construction.

It is primarily a method of forming a building with sectional members that contain not only the elements of enclosure, but, integrally the skeleton or supporting structure of the walls and roof connected to the enclosure or extended surface parts. I am aware that, portable, or "knocked down" buildings, are not a novelty, but the construction which I have shown in the drawings accompanying this specification, I believe is entirely new, of great utility, easily made and put together and possesses great strength and rigidity.

In forming the parts, while I prefer generally to use metal in solid sheets or expanded metal in parts on nearly all of the parts of the structure, yet other material may be used, such as composition fibre and concrete or combinations of such with metal or otherwise.

Generally, the sides and roof are designed to be built of panels of a similar style of construction.

It is also my purpose at times, to reinforce the strength of the triangular shaped column-girder joint, which is a particular feature of my design, by placing rods and concrete within the same.

While I have shown only a building of one story on the drawings, accompanying this specification, yet it is my purpose to use a similar type of panel to that shown for the sides and roof, for floor construction, placing the panels, preferably with the base of the triangle down as are the roof panels, and using suitable flooring on top of the construction and ceiling beneath, if desired.

At times, I make a double wall by fastening plates to the inner edge of the column joint.

For a more particular description of my invention, I refer to the drawings accompanying this specification, in which:

Figure 1, shows a side elevation of a small building built according to my method.

Figure 2, shows a cross view of the structure between the panels of the same, with knee-brace plates, ridge plates, and gable end plate or plates.

Figure 3, shows a sectional plan of the building shown by Figure 1, with front and back corner post construction diagramed.

Fig. 4 is an inside elevation of panel plates formed and connected in accordance with the invention, and Figure 9 is a vertical sec-

tional elevation taken along the line A—A of Figure 4.

Figure 5 is a plan view of the structure shown in Figures 4 and 9 and in addition to this figure includes dotted lines showing possible modifications of the structure.

Figure 6 shows a cross section of the coupling column, girder and rafter joint, which is preferably triangular in shape. This joint may be used with concrete filling and reinforcing rods, as shown, or without, according to the strength required.

Figure 7, shows a vertical side elevation of the joint, shown by Figure 6, and Figure 8 shows a front elevation view of the same.

Figure 10 illustrates a system whereby plates made in accordance with the invention may be used as molds for producing a concrete wall.

In all the figures, 1, 1, show the sides of the panels, and 7, 7, the flanged ends of the same.

Referring particularly to Fig. 6, it will be observed that the two panel plates have their edge portions bent or otherwise formed to substantially enclose between them a relatively large space which is of uniform cross section from one end of the panel to the other. As concerns the invention in its broader aspects, I do not limit myself to the exact form of this enclosed space, but I have found it highly preferable that this space be approximately triangular in form as shown. I further prefer that the plates be so formed or bent that the enclosed space will be located entirely at one side of the main plane of the plates. It will be understood that the formation of the plates in the way described provides a relatively large and strong supporting and reinforcing column at the joint between each two plates, thus providing a very stiff and rigid building structure.

I preferably connect the two plates together by two separate sets of bolts or other shear resisting fastenings located at opposite sides of the enclosed space. The inner set of bolts 4—4 preferably bears on washers 3—3.

In addition to the joint structure as already described, I prefer to also include a supplemental batten and coupling plate 2 which is clamped between the bent-over edges of the panel plates 1—1. Preferably as shown, this plate is T-shaped in cross section with the head of the T adjacent the outer surfaces of the panel plates.

5, 5, show reinforcing bars 6, 6, concrete, within the triangular shaped joint, which are used when strength requirements so indicate.

5 I preferably fill the triangular joint space with concrete, whether the reinforcing bars are used or not, as it preserves the metal and betters the construction generally. There are cases however where it may be 10 omitted to advantage.

8, 8, show knee-brace plates bolted or fastened in the triangular joint, with or without a part projecting outside of the outside surface of the structure and 9 shows a ridge 15 brace plate, bolted through the central part of the triangular joint against part 2.

10, shows a ridge plate fastened to the structure, 11, 11, show end formation sills and 14, 14, side sills, to which plates 1, 1, 20 are bolted, through flanges 7, 7.

12, 12, show back end posts construction being lapped over plate ends with a cross brace, forming a triangle in section.

13, shows a gable end plate, flanged inward 25 and along its upper edges bolted to parts 2, 2, of the last roof panel front and also one at the rear of the structure, fastened in a similar manner.

15, 15, show corner posts, covered with 30 metal and fastened to the last side front plates, 1, 1, and battens 2, 2. Parts 16, 16 are cornice gable ends bolted to parts 2, 2.

In Figure 5, 17, 17, show, in dotted lines, 35 plates with flanged edges fastened in the triangular joints by means of bolts through such flanges in the joints and such plates, forming a double wall. Figure 5 also illustrates how the main panel plates may be bent outward or inward as desired.

40 Figure 10, shows a method of producing a solid concrete wall by using plates 1, 1, shown by dotted lines, as the inside mold sides and 18, 18, as the outside of such mold sides, held together by short lengths of the 45 batten pieces 2, 2; such a mold may also be used for casting floors and roofs of the type shown by 19, or similar thereto.

20, shows an L brace stiffener for fastening on the plates 1, 1, when it is necessary to 50 prevent the buckling of such.

Where bolting is here mentioned, it is not intended to limit the fastening method to bolts alone, other methods may be used. The structure shown on the drawings would 55 be suitable for a small garage, with windows, and doors as shown between corner posts 15, 15.

It is assembled by fastening the upright 60 side plates 1, 1, to the sills 14, 14, and 11, rear, by bolting through the flanges 7, 7.

The triangular joints are coupled up, corners set and gable end plates fastened to the end roof panels. The roof panels are then placed with the plates 8, 8 and 9, 9, 65 in position and so on until completion.

If concrete is used in the joints, a grout mixture may be poured in during erection.

A finish is obtained to the ends by bolting on cornice gable end piece 16, 16.

The rafter plates which are flanged downward at the ends, bolt together, if desired, along the ridge, the part 10, in this case being made with lugs projecting downward between the flanged ends of the rafter plates, with holes in them, enabling bolts to be used 75 binding the ridge plate and the rafter ends together.

While the side and roof plates are here shown each as of one piece, the crimped triangular joint parts may be separately 80 constructed and fastened to the plates.

What I claim is:—

1. In a building structure, the combination of a series of vertical panel plates flanged inward at their tops and bottoms, 85 each pair of adjacent plates having their vertical edge portions bent to substantially enclose between them a space which is approximately triangular in cross section and which is located entirely at the inner side 90 of the main plane of the plates, a ground frame to which the bottom flanges are connected, and shear resisting fastenings for holding the each two adjacent plates together.

2. In a building structure, the combination of a series of vertical panel plates, each pair of adjacent plates having their vertical edge portions bent to substantially enclose between them a space which is approximately triangular in cross section and which is located entirely at the inner side 100 of the plane of the plates, a second series of panel plates similar in form to the aforesaid vertical plates and located above the latter to form another part of the building, vertical hip plates inserted in the joints between the panels to connect the first said vertical panels with the second said panels, and shear resisting fastenings for holding 105 all of the plates together.

3. In a building structure, the combination of a series of vertical panel plates, each pair of adjacent plates having their vertical edge portions bent to substantially enclose between them a space which is approximately triangular in cross section and which is located entirely at the inner side 110 of the plane of the plates, a series of plates T-shaped in cross section located respectively between each two adjacent panel plates with the head of the T adjacent the outer surfaces of the plates, a second series of panel plates similar in form to the aforesaid vertical plates and located above the latter to form another part of the building, a second series of plates T-shaped in cross section located respectively between each 115 two adjacent inclined panel plates with the head of the T adjacent the upper or outer 120 125 130

surfaces of the plates, vertical hip plates inserted in the joints between the panels to connect the first said vertical panels with the second said panels, and shear resisting fastenings for holding all of the plates together.

4. In a building structure, the combination of a series of vertical panel plates, each pair of adjacent plates having their vertical edge portions bent to substantially enclose between them a space which is approximately triangular in cross section and which is located entirely at the inner side of the plane of the plates, a second series 10 of panel plates similar in form to the aforesaid vertical plates and located above the latter to form another part of the building,

means for holding all of the plates together, and concrete filling the aforesaid triangular spaces between the several panels.

20

5. In a building structure, the combination of a series of panel plates, each pair of adjacent plates having their edge portions bent to substantially enclose between them a space which is uniform in cross section and which is located entirely at the inner side of the plane of the plates, a series of plates substantially parallel to the panels and engaging them at the inner sides 25 of the enclosed spaces, shear resisting fastenings for holding all of the plates together, and concrete filling the aforesaid spaces.

30

GEORGE WHITEFIELD CHANCE.
